UNITED STATES PATENT OFFICE.

ADRIAN WILLIS, OF MEIGS, GEORGIA.

ENGINE-VALVE LIFTER.

1,333,358.

Specification of Letters Patent.

Patented Mar. 9, 1920.

Application filed May 23, 1918. Serial No. 236,167.

To all whom it may concern:

Be it known that I, ADRIAN WILLIS, a citizen of the United States of America, residing at Meigs, in the county of Thomas and 5 State of Georgia, have invented new and useful Improvements in Engine-Valve Lifters, of which the following is a specification.

The invention seeks to provide, as its principal object, a device adapted for ready 10 attachment to an explosive engine valve to compress and hold under compression the spring of the latter, so that the valve may be readily moved from position. A further 15 purpose of the invention resides in the provision of a device of this character which consists of few parts, which effectively performs the function for which it is designed and which may be easily and cheaply manufactured.

20 Other and further purposes of the invention appear hereinafter wherein the construction is set forth in detail.

The invention, while shown and described in but one embodiment, is not to be restricted 25 to such. The right is reserved to vary the details of construction in any manner suggested by the actual practical use, provided such variations are compatible with the spirit of the subjoined claim.

30 In the accompanying drawings:

Figure 1 is a view in side elevation showing the practical application of the invention;

Fig. 2 is a plan view of the lifter *per se*;

35 Fig. 3 is a section on the line 3—3 of Fig. 1.

For the purpose of illustration there is shown the valve stem 1, the valve spring 2 and the valve stem guide 3 of an internal 40 combustion engine, such as is used in auto vehicles and the like. The improved tool, employed to relieve the stem 1 of the pressure of the spring 2 and to that end, it is formed with a body member A and the bell 45 crank lever B. The body member A is J-shaped, as shown and at the free end of its longer leg 4 it is bifurcated providing the fork 5. The shorter or curved leg 6 is also bifurcated for the purpose of providing the 50 two legs 7 between which the lever B may be pivotally mounted. A pin 8 passes through the two legs 7 and through the lever B, it being fixedly held at the two legs 7 but being loosely engaged by the lever B.

55 The longer leg 9 of the lever B is of curved formation, as shown, and at its free

end is formed with a fork 10. The shorter leg 11 is so formed that, when the fork 10 lies close to the fork 5, it may lie adjacent the inner curved face of the leg 6 of the body 60 member A.

This curved or shorter leg 6 of the body member has formed therein a threaded hole through which the thumb screw 12 passes, this thumb screw being so positioned that 65 its end will engage upon the side of the shorter leg 11 of the lever B.

In the use of the tool, the thumb screw 12 is backed out so that the two forks 10 and 5 may lie one on top of the other. The two 70 are then made to straddle the valve stem 1, whereupon the turning of the thumb screw 12 in the proper direction will serve to separate the two forks, thus compressing the valve spring 2 because of the fact that the 75 fork 5 lies upon the valve stem guide 3 while the fork 10 bears against the spring 2. It will thus be seen that the valve stem and of course the valve are relieved from the pressure of the spring, whereupon they may be 80 removed or handled with ease.

It will be observed that the peculiar construction of the tool permits the use of the thumb screw to be used to separate the two forks and thus hold the valve spring under 85 compression, but further than this, it is apparent that, the two forks being first inserted between the spring and the valve stem guide 3, a wedge may be inserted between the leg 10 of the lever B and the leg 6 of the body 90 member A, thus permitting the quick operation of the two forks and the consequent relieving of the valve of the pressure of the spring. Such a wedge may also be quickly 95 withdrawn to permit the resumption of the former positions of the valve and spring. This is convenient, of course, only when it is desired to raise the spring temporarily to test the valve for freedom of action and this subterfuge is mentioned only to cite one of 100 the many advantages of the peculiar construction of the tool.

The invention having been described, what is claimed as new and useful is:

A tool of the kind set forth comprising a 105 J-shaped body having a fork formed at the free end of its longer leg and being bifurcated at the free end of its shorter leg to leave two relatively short legs, a bell crank lever also having a fork formed at the free 110 end of its longer leg and having its shorter leg facing the inner face of the shorter leg

of the body member, the fulcrum point of the bell crank lever being positioned between the two relatively short legs on the shorter leg of the body member, a pin passing between the two said relatively short legs and through the bell crank lever, and a thumb screw carried by and threadingly engaging

the shorter leg of the body member and having its free end bear upon the shorter leg of the bell crank lever for the useful purpose 10 specified.

In testimony whereof I affix my signature.

ADRIAN WILLIS.
